UNITED STATES PATENT OFFICE.

JOSEPH H. STYLES, OF LONG ISLAND CITY, NEW YORK, ASSIGNOR TO DEFIANCE
BUTTON MACHINE CO., OF NEW YORK, N. Y., A CORPORATION OF NEW YORK.

SOCKET FOR SNAP FASTENERS.

Application filed November 8, 1921. Serial No. 513,705.

To all whom it may concern:

Be it known that I, JOSEPH H. STYLES, a citizen of the United States, residing at Long Island City, borough and county of 5 Queens, State of New York, have invented a certain new and useful Socket for Snap Fasteners, of which the following is a specification.

This invention is a socket for use in connection with a stud member of that type of 10 separable fastener commonly known as a ball and socket fastener and in extensive use on a large variety of apparel articles, such as gloves, caps, etc.

15 It is not unusual in prior socket members to employ a coating of one material or another, usually in the nature of enamel, upon the exposed surface of the cap which is an integral part of the socket member. As 20 socket members have been heretofore constructed, the coating on the cap disintegrates and cracks during the operation of applying the socket member to an article by the application of pressure, and this is due to the 25 fact that the contour and dimensions of the coated cap are modified by the pressure applied to said cap in the act of affixing the socket member to the article.

30 My invention seeks to eliminate the disintegration and cracking of the enamel coating on the cap of the socket member, and to this end I provide said socket member with a cap of such formation as to preclude distortion in that area covered by the coating.

35 Accordingly, my invention embodies a socket member the cap of which is provided with an inset shoulder or ledge positioned intermediate the enamel receiving surface 40 and certain infolded lips of said member. The cap of the socket member is attached to the article by an expanding eyelet adapted to be thrust through the material of the article and to be received within the space of 45 the cap, said eyelet being distorted by pressure applied in a direction to expand it within the infolded part of the cap so as to attach the latter and the eyelet to the article and without resulting in any deformation of 50 the cap, whereby the coating (enamel) remains intact and is free from cracking under the pressure required for the attachment of the socket member.

In the drawings—

55 Figure 1 is a plan view of the metal blank

adapted for the production of the cap of my socket member.

Figure 2 is a sectional view of the cup formation of the blank of Figure 1.

Figure 3 is an elevation of the next step 60 in the formation of the cap, and

Figure 3^a is a sectional view on an enlarged scale of a part of the cap shown in Figure 3.

Figure 4 is an elevation of the cap embodying my improvement, and

Figure 4^a is a sectional view on an enlarged scale of the cap shown in Figure 4.

Figure 5 is a plan view of the cap shown in Figure 4.

Figure 6 is a sectional view of the cap and an eyelet assembled for mutual co-operation when ready for attachment to an article, and

Figure 7 is a sectional view of the cap and eyelet after having been subjected to pressure and attached fixedly to the article.

As shown in Figures 6 and 7, my socket member comprises a cap A and an eyelet B, but in the production of the cap the metal is manipulated or fashioned so as to produce on said cap an inset shoulder or ledge a positioned intermediate the exposed surface of the cap and the infolded metal surrounding an orifice b within which the eyelet B is expanded for co-operation with the infolded metal in effecting the attachment of the cap without deforming the exposed surface of said cap.

As is usual in the art, the metal of the cap is blanked or stamped to produce a 90 blank C with lips or prongs c, see Figure 1, and this blank is drawn into cup shape at C' in Figure 2, and thereafter the lips or prongs c are infolded at c' in Figure 3 so as to produce the inner portion of the cap, 95 said infolded metal resulting in the orifice b on the inner side of the cap, whereas the outer side or exposed part of the cap is usually of convex formation, see Figures 3, 3^a, 4 and 4^a.

100 The essentially new feature of my cap is the ledge or shoulder a, shown in Figures 4 and 4^a, the same being intermediate the infolded portion c' and the exposed convex surface of the cap. This ledge or shoulder is produced during the operation of infolding the metal at c' or subsequently thereto, and said ledge or shoulder is in a plane radial (at a right angle) to the vertical transverse axial line of the cap. Said shoulder joins 110

2
the infolded part (which is adapted to be deformed by the application of pressure) with the exposed convex surface adapted to remain in an intact condition and to be free 5 from deformation under the application of pressure, the shoulder presenting a relatively stiff section of metal between the bendable and non-bendable portions of the cap.

In the operation of applying the socket 10 member to material, such as D in Figures 6 and 7, the eyelet B is thrust through said material, and inserted into the chamber of the cap, having passed through the orifice b. Pressure is now applied in the usual manner 15 and by appropriate means for the purpose of expanding eyelet B and upsetting the same, such expansion of the eyelet within the cap resulting in a displacement of the bendable portion c' of the cap so that the expanded 20 and upset eyelet and the expanded part c' of the cap are mutually affected for the attachment of the cap and eyelet fixedly to the material. It is to be noted, however, that the pressure has no appreciable effect 25 upon the ledge or shoulder a of the cap, nor upon the exposed portion of the cap to which the coating is applied, hence there is no deformation in the contour or dimensions of the exposed area of the cap by the force of 30 the pressure and consequently any coating on the exposed surface will not be affected by the attachment to the article, i. e., said coating is not cracked or disintegrated.

Obviously, the coating may be applied to 35 the cap by spraying, dipping, brushing or in any preferred mode, such coating being applied subsequently to the formation of the cap and prior to its assemblage with the eyelet for attachment to the article.

Having thus fully described the invention, 40 what I claim as new and desire to secure by Letters Patent is:

1. In a socket member, a cap provided with a ledge or shoulder extending inwardly

from the margin of a non-bendable exposed 45 face, said ledge or shoulder being positioned intermediate said exposed face and a bendable portion which latter is adapted to be distorted by the expansion of an attaching eyelet. 50

2. In a socket member, a cap provided with a ledge or shoulder extending inwardly from the margin of said cap, said ledge or shoulder being intermediate an exposed face of convex formation and a bendable portion 55 which is unitary with the ledge or shoulder, combined with an eyelet expanded within the bendable portion without distorting said exposed convex face of the cap.

3. In a socket member, a cap provided with an exposed face and with an infolded portion bendable under pressure, said cap being characterized by the presence of a ledge or shoulder positioned intermediate the bendable portion and the exposed face, said 60 ledge or shoulder extending inwardly from the margin of the exposed face and defining the limits of the bendable portion. 65

4. In a socket member, a cap provided with an infolded bendable portion and with 70 an exposed face of convex formation, said cap being provided with a ledge or shoulder extending inwardly from the margin thereof and said ledge or shoulder being positioned intermediate the bendable portion and the 75 convex face.

5. In a socket member, a cap provided with a ledge or shoulder intermediate a bendable portion and a non-bendable portion, 80 said ledge or shoulder extending inwardly from the margin of the non-bendable portion, combined with an eyelet expanded within the cap for displacing the bendable portion without distorting the non-bendable portion. 85

In testimony whereof I have hereto signed my name this 7th day of November, 1921.

JOSEPH H. STYLES.
